CLEMENT W. MULLER, OF MODESTO, CALIFORNIA

STATIONERY RACK

Application filed December 21, 1929. Serial No. 415,656.

This invention relates to stationery holding devices for use by stenographers and the like in a drawer of a typewriter desk.

The principal object of my invention is to provide a rack or holder for the purpose adapted to be removably fitted in or to be permanently arranged in connection with a drawer or similar container, by means of which a considerable quantity of stationery of different kinds may be maintained in flat neat piles and in segregated relation to each other. The rack also provides adjustable means for enabling sheets of different lengths such as are commonly used to be kept in such relationship in the rack that they can have no undue displacement and they will be retained in such a manner that one end of each kind or pile of sheets is always presented for ready engagement by the user.

Neatness and accessibility of the stationery is therefore enhanced, and the different kinds and sizes of sheets are always where needed and easily found, and they are not mixed up with the others as is too frequently the case. This of course also speeds up work, since no time is lost in hunting stationery of the required size and nature.

A further object of the invention is to provide a simple and inexpensive device and yet one which will be exceedingly effective for the purpose for which it is designed.

These objects I accomplish by means of such structure and relative arrangement of parts as will fully appear by a perusal of the following specification and claims.

In the drawing similar characters of reference indicate corresponding parts in the several views:

Fig. 1 is a perspective view of my improved rack as in operation.

Fig. 2 is a fragmentary perspective view of one of the separating and supporting members of the rack showing the adjustable back-stop mounted thereon.

Fig. 3 is a cross section on the line 3—3 of Fig. 2.

Referring now more particularly to the characters of reference on the drawing, the rack comprises a bottom sheet 1 which may be rigid or flexible, as desired, a number of other superposed and preferably flexible sheets 2, and a top cover sheet or flap 3, also preferably of a flexible nature. All these sheets are the same width or somewhat more than the width of any standard sheets of stationery, and the bottom sheet is considerably longer than the length of any such sheet. The other sheets, including the cover, while all terminating in the same vertical plane at their back edges are all successively shorter than the sheet 1 and than each other, so that while all the sheets vertically align with each other at the back, as stated, they are arranged in stepped relation to the sheet 1 and to each other at the front, as plainly shown in Fig. 1. A metal back plate 4 is rigidly connected to the sheet 1 and extends upwardly at the back of the same to the height of the cover 3; said cover 3 being flexibly connected to the plate at its upper end by a fabric hinge 5 or the like, while the intermediate sheets 2 are also connected in hinged relation to the back plate by similar means which holds said sheets in definitely spaced relation to each other while permitting them to be swung up if necessary.

Projecting upwardly from and secured to the forward edges of all the sheets 2 and also from the bottom sheet 1 a short distance from its forward edge are rigid upstanding flange elements 6 preferably of metal, and which form front stops for the stationery. These flange elements extend the full width of the sheets but are slightly greater in height than the fixed spacing between said sheets at the back. These elements are cut out intermediate their ends from the top to the bottom as shown at 7 so as to provide for engagement, by the fingers of the operator, of the adjacent forward edges of the sheets of stationery 8

supported by the corresponding sheets 2. The sheet 1 and all the sheets 2 except the topmost one are provided with transversely extending and longitudinally adjustable back 5 stop members for the stationery supported by the different sheets. These stop members are of metal and each constitutes an upstanding rigid flange 9, extending the full width of the sheet and the same height as the fixed spacing 10 between the sheets at the back. A horizontal flange 10 is formed with the flange 9 and rests on the sheet, facing toward the forward end of the same. Intermediate their ends the flanges 9 and 10 are cut out to form transverse-spaced pairs of longitudinally extending tongues 11 which project rearwardly or toward the back of the sheet and are disposed on a level slightly lower than the flange 9 or approximately the thickness of the sheet. 15 These tongues are adapted to be removably inserted in adjacent pairs of slots 12, longitudinally extending rows of which are provided in the sheets 1 and 2 toward the back ends of the same and spaced the proper distance apart transversely of the sheets and with respect to each other so as to simultaneously receive all the tongues on the back-stop member.

By means of these adjustable stops the distance between the fixed front flanges 6 and said stops may be gaged to substantially correspond to the length of the sheets of stationery supported on the corresponding sheet 2 and disposed between adjacent sheets, so that the stationery will project a sufficient distance ahead of the relatively short sheet 2 above so as to render the stationery readily accessible to the user without her having to lift up the parts above to get at the same. A portion of each pile of stationery being visible at all times it is unnecessary for the user to spend any time in hunting for any particular kind or size of sheet. These stops also provide means for supporting the flexible sheets at the back of the stationery holding area thereof, independent of their connection with the back plate 4 so that the weight of the superimposed stationery 8 down on the supporting sheets will not pinch the stationery below at the back and so tend to prevent ready withdrawal of the same from the front end.

By reason of the above construction and arrangement of parts it is possible, with a rack provided with a reasonable number of 55 supporting and separating sheets, to hold piles of the ordinary forms and sizes of stationery, in separated and relatively non-movable relation to each other, and in such a manner that a sheet of any kind or size 60 may be readily withdrawn without disturbing any others. Though it is not essential I preferably use the space between the upper sheet 2 and the cover flap 3 as the space for retaining envelopes 13, as such space is naturally the shortest in the rack and is better

adapted for this purpose than the others. The envelopes fit in this space in transversely spaced piles, and the flange member 6 at the front edge of the corresponding supporting sheet 2 is therefore provided with two of the cut-out portions 7, transversely separated from each other, so as to enable the envelopes from the corresponding piles to be readily engaged and withdrawn. The dimensions of the bottom sheet 1 (the largest one of the device), and the total height of the back are such that the device will readily fit into a standard typewriter desk drawer. At the same time, as previously indicated, the rack may be actually built into the drawer if desired. In either case the positioning of the front stop flange 6 on the lower sheet 1 some distance from the forward edge of said sheet, enables the user to readily engage the stationery supported on said sheet without cramping the fingers or possibly crumpling while attempting to pick up a sheet.

From the foregoing description it will be readily seen that I have produced such a device as substantially fulfills the objects of the invention as set forth herein.

While this specification sets forth in detail the present and preferred construction of the device, still in practice such deviations from such detail may be resorted to as do not form a departure from the spirit of the invention, as defined by the appended claims.

Having thus described my invention what I claim as new and useful and desire to secure by Letters Patent is:

1. A stationery rack including a plurality of stationery supporting and separating members, means flexibly supporting said members at the back in fixedly spaced relation to each other in a common vertical plane, and flanges mounted on and projecting upwardly from said members intermediate their ends.

2. A stationery rack including a plurality of stationery supporting and separating members, means flexibly supporting said members at the back in fixedly spaced relation to each other in a common vertical plane, the members at their front ends being successively shorter than each other from the bottom one upwardly, and flanges projecting upwardly from the front ends of the members to a height not less than the fixed spacing between the members at the back.

3. A stationery rack including a plurality of stationery supporting and separating members, means flexibly supporting said members at the back in fixedly spaced relation to each other in a common vertical plane, flanges projecting upwardly from the members at their forward ends, and other flanges, adjustable lengthwise of the members, mounted on and projecting upwardly from the same intermediate their ends, the height of said last named flanges being substantially

equal to the fixed spacing between the members at the back.

4. A stationery rack including a plurality of stationery supporting and separating members, hinge means flexibly supporting said members at the back end for vertical swinging movement and maintaining the members definitely spaced at said end, and elements mounted on and extending between adjacent members ahead of said back end of a height to maintain them substantially parallel to each other without interfering with their upward swinging movement.

In testimony whereof I affix my signature.

18 CLEMENT W. MULLER.
